CHRISTIAN AALBORG, OF WILKINSBURG, PENNSYLVANIA, ASSIGNEE TO WESTINGHOUSE ELECTRIC AND MANUFACTURING COMPANY, A CORPORATION OF PENNSYLVANIA.

PERCOLATING APPARATUS.

1,194,115.

Specification of Letters Patent.

Patented Aug. 8, 1916.

Application filed February 17, 1913. Serial No. 748,783.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Percolating Apparatus, of which the following is a specification.

My invention relates to electrically heated liquid-containing vessels of the percolator type and it has special reference to removable heating devices therefor.

One object of my invention is to provide a device of the above-indicated class which shall be simple and economical in construction, reliable and effective in operation, and conveniently portable in form.

Another object is to provide a single and reliable automatic means for controlling the percolating liquid, including an automatic means for aiding the usual process of percolation.

It is old in the art to provide a percolating element adapted for immersion in liquid; and likewise the principle of percolating apparatus of the same class as that hereinafter described, is deemed to be so well known as not to require any further exposition here.

According to my invention, I provide a check valve mechanism located centrally in the lower surface of the percolating element, that is, directly below the mouth of the fountain tube and adapted to permit only the entrance of liquid. The valve is designed to operate automatically during the process of percolation and to be dependent upon the relative pressures on its two faces. Moreover, by virtue of the peculiar construction of the fountain tube and the cylinder member surrounding the same, a closed annular chamber is formed, which, during the process of percolation, acts as a steam compression chamber, thus aiding the process, as hereinafter described.

In the accompanying drawing Figure 1 is a vertical sectional view of a portion of a percolating element embodying my invention; and Fig. 2 is a similar view of a modification thereof.

Referring to the drawing, a circular body member 1 is composed of a plurality of similar independent disks 2 of good-heat-conducting material severally having oppositely-disposed hollow hubs 3. Intermediate

The specific structure of the element 4 is not material to my present invention and, consequently it will not be further described. Engaging the edges 5, of the disks 2 and bent over the outer portions of their faces 6 to fit tightly around the same, is a metal strip 7 for holding the disks in position. The lower portion of an upright hollow cylinder 8 is fitted tightly within the hollow hubs 3. A cap 9 closes the upper end of the cylinder 8, and a check valve 10 cooperates with a seat 11 to close the lower end thereof. A central well 12 is thus formed, into which extends a fountain tube 13 to a point slightly above the valve 10, thereby producing a chamber 9a in the upper portion of the cylinder 8. The tube 13 is provided with a plurality of small oppositely-disposed side openings 14, or at least one such opening, near lower end 15 thereof which take a part 75 in the process of percolation as hereinafter described.

Surrounding the body member 1 on all sides, is an incasing member 16 having a raised central portion 17. A suitable air space 18 between the body member 1 and the incasing member 16 serves as a heat insulator, whereby practically all the heat emitted by the heater element 4 is transmitted through the conducting disks 2 to the lower part of cylinder 8, which contains the isolated body of liquid to be heated. As is usual with this class of heater, a liquid-proof tube 19, containing leads 20 to the heater element 4, extends through an opening 21 in the incasing member 16. A plurality, preferably three, of outwardly-projecting circular bosses 22 on the bottom wall 23 of the incasing member 16 serve as supports therefor.

The operation of the device is substantially as follows: When the element is immersed, a body of liquid enters the well 12 through the opening with which the valve 10 cooperates. The level of the liquid in the fountain tube 13 may rise to the height of the liquid outside of the element, but the level in the cylinder 8 outside of said tube is limited to a height slightly above the openings 14 therein, by reason of the pressure of the medium confined in the chamber 9a. The said medium may be air, steam or a mixture of both, as will be evident from the following description. The heat emitted by the electric heating element 4 raises the tem-

perature of the isolated body of liquid in the cylinder 8. A portion of said liquid is flashed into steam, filling the chamber 9^a and exerting pressure on the body of liquid to force a portion of the same up through the tube 13. In addition, the familiar method of percolation—the projection of liquid up the tube 13 along with the steam—occurs. The rapidly moving liquid passing the openings 14 in the wall of the tube 13 draws a portion of the outer liquid through said openings and up the tube, according to the well-known ejector principle. The consequent decrease of pressure in the cylinder 8 permits the outer pressure to open the valve 10 for an instant, when more liquid flows in, pressures become equalized, and the valve 10 drops back to its seat 11. As is understood, the above process recurs at frequent intervals throughout the time that electric energy is supplied to the heater.

In the modification of my invention shown in Fig. 2, the sole difference from the percolating element already described, resides in the construction of the lower end of the cylinder 8, which has a threaded opening 24 therein adapted to engage a threaded base 25 provided with a small concentrically disposed open tube 26 extending up within the fountain tube 13 and having a mouth 27 located a short distance above the holes 14. The device operates similarly to the one hereinbefore described except for the method of admission of the liquid, which is as follows: While the body of liquid in the cylinder 8 is being heated, the level of the liquid in the fountain tube 13 is above the mouth 27 of the small tube 26 and no inward flow occurs. However, when a body of liquid is projected up the tube by the expansion of the steam in the chamber 9^a the pressure at the mouth 27 is decreased and a portion of the outer liquid flows in, the action being aided by the aspirating effect of the upwardly-projected body.

Those skilled in the art will readily understand that my invention is not restricted to the specific structural details and arrangement of parts herein shown and described, and it is evident that many modifications may be effected therein without departing from the spirit and scope of my invention.

I claim as my invention:

1. A heating apparatus embodying a well for containing liquid, means for heating said liquid, a tube extending into said well, means near the lower end of the said well for admitting the liquid thereto, and means for limiting the height of said liquid therein.
2. A heating apparatus embodying a centrally-disposed well for containing liquid, means for heating said liquid, a fountain tube of relatively small diameter extending into said well, means near the lower end of the said well for intermittently admitting

liquid thereto, and means for limiting the height of said liquid in a portion of said well.

3. A heating apparatus embodying a centrally-disposed well for containing liquid, means for heating said liquid, a fountain tube of relatively small diameter extending into said well and nearly to the bottom thereof and dividing the well into an inner and an outer chamber, one of which has a closed end, means near the lower end of the said well for intermittently admitting the liquid thereto, and means for limiting the height of said liquid in the closed chamber.

4. A heating apparatus embodying a well for containing liquid, means for heating said liquid, a tube of relatively small diameter extending into said well for dividing the well into an upper steam compression-chamber and a lower liquid-containing chamber.

5. A heating apparatus embodying a well for containing liquid, means for heating said liquid, a fountain tube of relatively small diameter extending into said well and having an opening near the lower end thereof, said tube serving to divide said well into a steam-compression chamber above said opening and a liquid-containing chamber below the same.

6. An electric heater adapted for immersion in a liquid and comprising a body member of relatively good heat-conducting material, a centrally-disposed hollow member in engagement therewith, a fountain tube extending nearly to the bottom of said hollow member, means for heating the said body member, and heat insulating means partially surrounding the same.

7. An electric heater adapted for immersion in a liquid and comprising a body member of relatively good heat-conducting material, a centrally-disposed upright cylindrical member in intimate contact therewith, a fountain tube extending through the upper end of said cylindrical member and nearly to the lower end thereof, means for heating the said body member, and a heat-insulating medium surrounding a portion thereof.

8. An electric heater adapted for immersion in a liquid and comprising a body member of relatively good heat-conducting material having a central opening, a hollow upright cylindrical member of similar material fitting tightly within said opening and having a closed upper end, a fountain tube extending through said upper end and nearly to the lower end thereof to form an annular chamber, and a heating element intimately associated with said body member and surrounding said cylindrical member, said body member being surrounded by a heat-insulating body of air.

9. In a percolator, the combination with a body member of good heat-conducting ma-

terial, and a heater element associated therewith, of a centrally disposed hollow member in engagement with said body member, a fountain tube extending nearly to the bottom of said hollow member, and means for intermittently opening and closing access thereto.

10. In a percolator, the combination with a body member of good heat-conducting material and a heater element associated therewith, of a centrally disposed hollow cylindrical member in intimate contact with said body member, a fountain tube extending through the upper end of said cylindrical member and nearly to the lower end thereof, and means for opening and closing the access thereto.

11. In a percolator element adapted for immersion in a liquid, the combination with a body member of good heat-conducting material having a central opening, and a heater element intimately associated with said member, of a hollow upright cylinder of good heat-conducting material fitting tightly within said opening and having a closed upper end, a fountain tube extending through said upper end and nearly to the lower end of said cylinder to form an annular chamber, and means adapted to permit one-way flow of liquid to said cylinder.

12. In a percolator element adapted for immersion in a liquid, the combination with a body member of good heat-conducting material having a central opening, and a heater element intimately associated with said member, of a hollow upright cylinder of good heat-conducting material having the lower portion thereof fitting tightly within said opening and provided with a closed upper end, a fountain tube extending through said upper end and nearly to the lower end of said cylinder and provided with a side opening in its lower portion, and means centrally disposed in the lower end of said cylinder for controlling the admission of liquid thereto.

13. In a percolator element adapted for immersion in a liquid, the combination with a body member of good heat-conducting material having a central opening, and a heater element intimately associated with said member, of a hollow upright cylinder of good heat-conducting material having the lower portion thereof fitting tightly within said opening, a cap closing the upper end of said cylinder, a fountain tube extending through said cap and nearly to the lower end of said cylinder and provided with a side opening in its lower portion, and liquid-admitting means centrally located in the lower end thereof.

14. In a percolator, the combination with a body member of good heat-conducting material, of a fountain tube concentrically disposed in said body member, and a valve

mechanism located centrally in the lower side of said body member.

15. In a percolator, the combination with a body member of good heat-conducting material, of a hollow member centrally disposed within said body member and having a bottom wall provided with an opening, a fountain tube extending within said hollow member, and a check valve mechanism located centrally in said bottom wall and adapted to selectively cover or uncover said opening therein.

16. In a percolator element adapted for immersion in a liquid, the combination with a body member of good heat-conducting material, of a hollow upright cylindrical member concentrically located within said body member and having a bottom wall provided with an opening, a fountain tube extending within said cylindrical member, and an entrance check valve mechanism located centrally in said bottom wall and dependent for action upon the relative pressures of the liquid outside and inside the cylindrical member.

17. In a percolator element adapted for immersion in a liquid, the combination with means for heating said element, of a centrally-disposed hollow member intimately associated with said heating means, a fountain tube provided with a side opening in its lower portion and extending through the upper end of said hollow member and nearly to the lower end thereof to form a closed annular chamber, and a valve mechanism located centrally in the lower end of said hollow member.

18. In a percolator element adapted for immersion in a liquid, the combination with means for heating said element, of a hollow upright cylinder of good heat-conducting material having the lower portion thereof intimately associated with said heating means, a cap closing the upper end of said cylinder, a fountain tube extending through said cap and nearly to the lower end of said cylinder and provided with a side opening in its lower portion and liquid admitting means centrally located in the lower end of said cylinder and dependent for action upon the pressure of the liquid.

19. An electric heater adapted for immersion in a liquid and comprising a body member of relatively good heat-conducting material, a centrally-disposed hollow member in engagement therewith, a fountain tube having a side opening in its lower portion and extending nearly to the bottom of said hollow member, means for heating the said body member, and heat-insulating material partially surrounding the same.

20. In a percolator, the combination with a body member of good heat-conducting material and a heater element associated therewith, of a centrally-disposed hollow mem-

ber in engagement with said body member, a fountain tube having a side opening in its lower portion and extending nearly to the bottom of said hollow member, and means for intermittently opening or closing access thereto.

21. In a percolator, the combination with a body member of good heat-conducting material, of a fountain tube concentrically disposed in said body member and having a side opening in its lower portion, and a valve mechanism located centrally in the lower side of said body member.

22. In a percolator element adapted for immersion in a liquid, the combination with a body member of good heat-conducting material, of a hollow, upright, cylindrical member concentrically located within said body member and having a bottom wall provided

20 with an opening, a fountain tube having an opening in the lower portion of the wall thereof and extending within said cylindrical member, and liquid admitting means centrally located in said bottom wall and

25 dependent for action upon the relative pressure of the liquid outside and inside said cylindrical member.

23. In a percolator element adapted for immersion in a liquid, the combination with

20 means for heating the same, of a body member having a central opening and compris-

ing a plurality of circular plates and a ring member adapted to engage the edges of said plates, a hollow upright cylinder fitting tightly within said opening and having a 35 closed upper end, a fountain tube extending through said upper end and nearly to the lower end of said cylinder to form an annular chamber, and means for admitting liquid to said cylinder.

24. In a percolator element adapted for immersion in a liquid, the combination with means for heating the same, of a body member having a central opening comprising a plurality of superposed circular plates and a ring adapted to fit closely over the edges of said plates, a hollow upright cylinder having the lower portion thereof fitting tightly within said opening, a cap closing the upper end of said cylinder, a fountain tube extending through said cap and nearly to the lower end of said cylinder and provided with a side opening in its lower portion, and means for admitting liquid to said cylinder.

In testimony whereof, I have hereunto subscribed my name this 7th day of Feb. 1913.

CHRISTIAN AALBORG.
